UNITED STATES PATENT OFFICE.

CARL A. WENDELL, OF JOLIET, ILLINOIS.

DRIER.

1,187,585.

Specification of Letters Patent. Patented June 20, 1916.

Application filed June 12, 1915. Serial No. 33,794.

To all whom it may concern:

Be it known that I, CARL A. WENDELL, a citizen of the United States, residing at Joliet, in the county of Will and State of Illinois, have invented a certain new and useful Improvement in Driers, of which the following is a specification.

My invention relates to driers particularly intended for drying coal and other such substances.

It is illustrated in the accompanying drawing, wherein—

Figure 1 is a vertical transverse section; Fig. 2 is a plan view with parts broken away to show the interior structure; Fig. 3 is a detail section on the line 3—3 of Fig. 1; Fig. 4 is an enlarged detail of the discharging mechanism; Fig. 5 is an enlarged detail.

Like parts are indicated by the same letter in all the figures.

A, A are the frame pieces on which the working parts are mounted.

B is a vertical shaft driven from the pulley B¹ and provided with the gear B² which meshes with the gear B³ on the shaft B⁴. B⁵ is a somewhat larger gear wheel on the shaft B⁴ meshing with a small pinion B⁶ on the sleeve B⁷, which is mounted on the shaft B.

C, C are spouts which are mounted on and carried by the sleeve.

C¹ is a supply chute which opens into the central ring C² whence the spouts radiate downwardly and outwardly.

D is a cover or casing for the operating parts.

E is a cone-shaped shield supported on the collar E¹ through which the shaft passes and it rests upon the cup E² in the central frame-piece or hub E³. At the outer edge of the cone is the annular floor E⁴. A similar annulus F is placed above the floor. It serves as the roof of the annular chamber into which the spouts open. It is continuous with the cone-shaped piece F¹ and thus the parts which form the annular chamber are rotated with the shaft by means of the collar E¹ fixed thereon. The spouts are rotated in the same direction, but because of the different relation between the gear B² and B³ and the gear B⁵ and B⁶ the spouts travel slightly faster than the annular chamber.

In the bottom of the covering D and between its outer wall and the wall of the ring G is a water chamber G¹ with a drip pipe G². The ring G together with the hopped

portion G³ constitutes a dried material receptacle.

J is the top, J¹ the inclined walls and J² a pipe which leads from the movable receptacle which is mounted upon the vertical pivot rod J³ which passes through the edge of the annular top F and the edge of the annular bottom E⁴ so that the water receptacle is pivotally mounted and supported between the top and bottom. K is a perforated screen which closes the remaining side of the receptacle. The pivot rod J³ projects downwardly from the bottom and has secured thereto a cross-bar L from which projects an arm L¹ carrying a weight L². From the two ends of the cross-bar L passes chains L³, L⁴ to the two ends of a similar bar L⁴ which is secured to the elbow lever L⁵ which passes up through the bottom E⁴. The other end of this elbow lever projects into the path of a roller M on a tripping arm M¹ which projects from the spout C in the direction of travel.

These several parts can, of course, be greatly varied without departing from the spirit of my invention and I wish my drawings to be taken as in a sense diagrammatic and intended to illustrate the general ideas of this invention without confining myself to the particular device or structure shown.

The use and operation of my invention are as follows: Assuming that the parts are constructed substantially as shown, the machine set in operation, there will be an annular material compartment between the floor E⁴ and the roof F and the series of screens which form the front side of the several water receptacles. In operation this material receptacle and this series of water receptacles will be rotated in a given direction, while the spouts will be rotated in the same direction but a little faster. The actual speed and the relative speed can be anything desired or suitable for any given material. Obviously if the material to be dried is now fed into the chute, it would ascend into the spouts and will pass through them into the annular receptacle chamber, and since the spouts travel a little more rapidly than the receptacle or channel, the same will be gradually filled until there will be a practically continuous and substantially uniform ring of material in the annular material receptacle. The speed of rotation should be such that centrifugal action will force the water or moisture from the mate-

rial through the screen into the several water receptacles and here the same centrifugal force will cause it to flow out of the several pipes and into the water chamber.

5 When the arm N^1 of a given spout proceeds until its roller strikes the upper end of the elbow lever M^5 , the latter will be rotated on its vertical axis and thus the cross-bar L^4 will be rotated and so also the cross-bar L . This will tilt the arm L^1 and the weight L^2 to one side and at the same time tilt the water receptacle associated therewith until the screen K is placed at an angle to the tangent of the circle of rotation. This 10 will also separate the otherwise closely approximate vertical edges of the water receptacles and will permit the dried material on the particular screen section in question to be discharged by centrifugal force against the ring G and down into a hopper G^3 . As 15 soon as the arm and its roller escapes from contact with the elbow lever the weight L^2 will responsive to centrifugal action resume the position shown in Fig. 5 and restore the 20 parts to their position shown in the drawings. Immediately after this action the spout which discharges in the direction of travel will fill said receptacle with moist material and thus the action will proceed 25 continuously.

I claim:

1. In a drier the combination of a material supplying device with a drying compartment to which it delivers and means for 30 rotating them differentially in the same direction, said drying compartment having a series of separately mounted screen sections and means for successively tilting them responsive to such differential motion to discharge the dried material from them by 35 centrifugal force, a funnel shaped liquid compartment immediately behind and closed by the screen and mounted for rotation in unison with the screen.
2. In a drier the combination of a material supplying device with a drying compartment to which it delivers and means for 40 rotating them differentially in the same direction, said drying compartment having a series of separately mounted screen sections and means for successively tilting them responsive to such differential motion to discharge the dried material from them by 45 centrifugal force, a funnel shaped liquid compartment immediately behind and closed by the screen and mounted for rotation in unison with the screen, a discharge spout 50 leading from said compartment, and a receiving channel into which said spout discharges and with which it is always in register.
3. In a drier the combination of a material supplying device with a drying compartment to which it delivers and means for 55 rotating them differentially in the same direction,

reception, said drying compartment having a series of separately mounted screen sections and means for successively tilting them responsive to such differential motion to discharge the dried material from them by 70 centrifugal force, a funnel shaped liquid compartment immediately behind and closed by the screen and mounted for rotation in unison with the screen, a discharge spout leading from said compartment, and a receiving channel into which said spout discharges and with which it is always in register, said channel being opened toward the discharge spout.

4. In a drier the combination of a material supplying device with a drying compartment to which it delivers and means for 80 rotating them differentially in the same direction, said drying compartment having a series of separately mounted screen sections 85 and means for successively tilting them responsive to such differential motion to discharge the dried material from them by centrifugal force, a funnel shaped liquid compartment immediately behind and closed 90 by the screen and mounted for rotation in unison with the screen, a discharge spout leading from said compartment, and a receiving channel into which said spout discharges and with which it is always in register, said channel being opened toward the discharge spout, and above the normal line 95 of flight of the material as it discharges centrifugally from the drying receptacle.

5. In a drier the combination of a material supplying device with a drying compartment to which it delivers, means for 100 rotating them in the same direction differentially, said drying compartment being bounded by a series of separately mounted 105 screen sections, means for successively rotating such sections responsive to such differential motion to drive the discharge material from them by centrifugal force, a receptacle for the reception of such discharge 110 material, such receptacle being in communication with the interior of the drying compartment only when such screen section is rotated for discharge, a receptacle for the 115 reception of the liquid discharged from the material as it is dried, said receptacle being always in communication with the outside of the screen section independent of the position thereof.

6. In a drier the combination of a material supplying device with a drying compartment to which it delivers, means for 120 rotating them in the same direction differentially, said drying compartment being bounded by a series of separately mounted 125 screen sections, means for successively rotating such sections responsive to such differential motion to drive the discharge material from them by centrifugal force, a receptacle for the reception of such discharge 130

- material, such receptacle being in communication with the interior of the drying compartment only when such screen section is rotated for discharge, a receptacle for the reception of the liquid discharge from the material as it is dried, said receptacle being always in communication with the outside of the screen section independent of the position thereof, said screen being mounted for 10 rotation with respect to the drying compartment on a vertical axis.
7. In a drier the combination of a material supplying device with a drying compartment to which it delivers, means for rotating them in the same direction differentially, said drying compartment being bounded by a series of separately mounted screen sections, means for successively rotating such sections responsive to such differential motion to drive the discharge material from them by centrifugal force, a receptacle for the reception of such discharge material, such receptacle being in communication with the interior of the drying compartment only when such screen section is rotated for discharge, a receptacle for the reception of the liquid discharged from the material as it is dried, said receptacle being always in communication with the outside of the screen section independent of the position thereof, said screen being mounted for 15 rotation with respect to the drying compartment on a vertical axis, the means for rotating and controlling such sections comprising an axial shaft extending outwardly beyond such section, lever arms mounted thereon, a weighted balance arm mounted thereon adapted to hold the section closed by centrifugal force, a controlling shaft, a lever carried thereby, operating means in opposition to said lever and two controlling levers mounted on said 20 shaft, flexible means between each of such controlling levers and one of the controlling levers on the section axial shaft.
- 25 8. In a drier the combination of a material supplying device with a drying compartment to which it delivers, means for rotating them in the same direction differentially, said drying compartment being bounded by a series of separately mounted screen sections, means for successively rotating such sections responsive to such differential motion to drive the discharge material from them by centrifugal force, a receptacle for the reception of such discharge material, such receptacle being in communication with the interior of the drying compartment only when such screen section is rotated for discharge, a receptacle for the reception of the liquid discharged from the material as it is dried, said receptacle being always in communication with the outside of the screen section independent of the position thereof, said screen being mounted for 30 rotation with respect to the drying compartment on a vertical axis, the means for rotating and controlling such sections comprising an axial shaft extending outwardly beyond such section, lever arms mounted thereon, a weighted balance arm mounted thereon adapted to hold the section closed by centrifugal force, a controlling shaft, a lever carried thereby, operating means in opposition to said lever and two controlling levers mounted on said shaft, flexible means between each of such controlling levers and one of the controlling levers on the section axial shaft.
- 35 9. In a drier the combination of a material supplying device with a drying compartment to which it delivers, means for rotating them in the same direction differentially, said drying compartment being bounded by a series of separately mounted screen sections, means for successively rotating such sections responsive to such differential motion to drive the discharge material from them by centrifugal force, a receptacle for the reception of such discharge material, such receptacle being in communication with the interior of the drying compartment only when such screen section is rotated for discharge, a receptacle for the reception of the liquid discharged from the material as it is dried, said receptacle being always in communication with the outside of the screen section independent of the position thereof, said screen being mounted for 40 rotation with respect to the drying compartment on a vertical axis, the means for rotating and controlling such sections comprising an axial shaft extending outwardly beyond such section, lever arms mounted thereon, a weighted balance arm mounted thereon adapted to hold the section closed by centrifugal force, a controlling shaft, a lever carried thereby, operating means in opposition to said lever and two controlling levers mounted on said shaft, flexible means between each of such controlling levers and one of the controlling levers on the section axial shaft.

In testimony whereof, I affix my signature in the presence of two witnesses this 24th day of May 1915.

CARL A. WENDELL.
